(57) **CLAIM**

The ornamental design for a wireless charging stand, as shown and described.

DESCRIPTION

FIG. 1 is a perspective view of a wireless charging stand showing our new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view showing the wireless charging stand in a use state;

FIG. 10 is another perspective view showing the wireless charging stand in a second use state; and,

FIG. 11 is an enlarged view of the wireless charging stand shown within the area designated as 11 in FIG. 3.

The broken lines in the drawings depict portions of the wireless charging stand that form no part of the claimed design.

1 Claim, 11 Drawing Sheets
